UNITED STATES PATENT OFFICE.

EDWARD A. BOOHER, OF WEST AUSTINTOWN, OHIO.

TIE FOR MINE TRACKS.

Application filed July 28, 1923. Serial No. 654,390.

To all whom it may concern:

Be it known that I, EDWARD A. BOOHER, a citizen of the United States, residing at West Austintown, in the county of Mahoning and State of Ohio, have invented certain new and useful Improvements in Ties for Mine Tracks, of which the following is a specification, reference being had to the accompanying drawings.

10 This invention relates to ties, and particularly to ties designed for the support of mine rails such as the rails in a "room" or that portion of the mine from which coal has been excavated.

15 One of the objects of this invention is to provide a very simply constructed tie which may be made of steel and by which the rails are securely clamped in place, the tie being so constructed that the rail clamps may be 20 readily detached from the tie to permit the removal of the rails.

25 A further object is to provide a tie of this description which is adapted for use with plain rails or at joints, and in the latter case is adapted to be used as a lug joint tie or with bolts at the joint as desired.

30 A still further object is to provide a construction of this character which will permit one of the rail clamps to be readily detached or put in place to permit the ready detachment of the rail and thereby permit the ready re-arrangement of the tracks.

35 Other objects will appear in the course of the following description.

40 My invention is illustrated in the accompanying drawings, wherein:—

Figure 1 is a top plan view of a mine track tie constructed in accordance with my invention, one of the rails being partly in section;

45 Figure 2 is a section on the line 2—2 of Figure 1;

Figure 3 is an elevation of the construction shown in Figures 1 and 2;

50 Figure 4 is a perspective view of the clamp 17;

Figure 5 is a fragmentary perspective view of the flange 18, showing the manner in which the studs 27 are formed;

55 Figure 6 is a fragmentary perspective view showing another manner of constructing the plate 17;

Referring to these drawings, 10 designates a tie which is preferably of metal U-shaped in cross section to provide the side flanges 11. Obviously this tie may have any suitable

length. Attached to the ends of the tie are the plates 12. These plates may be riveted to the tie by means of the rivets 13. These plates rest flat against the tie at their outer ends and then incline upward and forward, as at 14. The inner end of the plate is upwardly angled or extended, as at 15, and the sides of the plate are upwardly angled or extended, as at 16, to form abutments against 60 which the transverse member or flange 15 bears. This flange is preferably longer than the distance between the upwardly extending abutments 16 so as to extend preferably slightly beyond the tie itself. It is obvious, 65 however, that this is not a necessary feature. The plate 12 with its flanges 15 and 16 might be cast in one piece or formed of sheet metal.

Coacting with these clamping members 12 are clamping members 17. These are each 70 formed of a plate of metal angularly bent at its end, as at 18, to confront the portion 15 of the plate 12. Side flanges 19 are bent up from the plate 17 and abut at their ends against the flange 18 to support the same and 75 strengthen the plate. Adjacent its end remote from the flange 18 the plate is formed with a transversely extending depression 20, and extending longitudinally through the plate is a slot 21 which intersects this depression. The tie 10 is formed inward of each 80 of the rail clamps with a transversely extending depressed portion 22, and intersecting this depressed portion is a slot 23, the material of which has been bent upward, as 85 at 24, to form an upwardly extending eye. The slot 21 is of sufficient width to receive this eye and the depressed portion 20 of the plate 17 fits in the depressed portion 22 of the tie. A pin 25 under these circumstances 90 passes through the eye and extends laterally over the face of the depressed portion 20, thus locking the clamping member 17 securely in place. This clamping member 17 is also formed so that when it is clamped in 95 place the flange of the rail A will fit beneath the plate 17.

In Figure 1, I have shown one end of the tie as being formed with the clamping plates 17 and 12, as before described, but I have 100 also illustrated the flange 15 at the other end as formed at its ends with openings 26 and have shown the flange 18 as provided with parallel studs 27 which extend through these 105 openings 26 and through openings in the adjacent ends of the two rails, thus constituting a joint clamp. Thus in a single tie one end 110

of the tie may be formed to engage and hold the joint closed and the opposite end of the tie may be formed with clamps which will engage the intermediate portion of a rail. 5 Obviously ties may be formed which at both ends will engage the intermediate portion of the rail if desired.

I do not wish to be limited to the use of the studs 27 in conjunction with the perforations 26 in plate 15, but I may use, as 10 illustrated in Figure 6, a plate 17, the extremities of the flange 18 being formed with openings 28 which will confront the openings 26 and through which bolts may be 15 passed to hold the clamps in engagement with the abutting rails at the rail joint. I have illustrated in Figure 1 the studs 27 as being formed as shown in Figure 5, that is by lugs projecting longitudinally from the 20 flange 18, these lugs being bent into a cylindrical form so as to pass through the openings 26. Obviously I do not wish to be limited to this.

I claim:—

- 25 1. A metallic tie of the character described having downwardly extending side flanges, the face of the tie at a distance from an end being provided with a transversely depressed portion and an upstanding eye beneath which the depressed portion extends, 30 a rail clamping member attached to the end of the tie and having a vertical portion adapted to bear against the web of a rail, a clamping member including a vertical portion adapted to confront the vertical portion 35 of the first named clamp and having a base adapted to rest upon the tie, this base having a transversely depressed portion, a slot intersecting said depressed portion and adapted to receive the eye, and a locking member adapted to pass across said depressed portion of the clamping member and beneath said eye.
- 40 2. A metallic tie of the character described having spaced from one end a transversely extending depressed portion and having struck up from the tie an upwardly extending eye intersecting said depressed portion, 45 a rail clamping member attached to one end of the tie and having a vertical flange extending transversely of the tie, the ends of the flange being perforated, a second 50 clamping member having a base and an upwardly extending flange, the base being formed with a transversely extending de- 55 pressed portion adapted to fit in the depressed portion of the tie and with a longi-

tudinally extending slot adapted to receive said eye, the transversely extending flange of the last named clamp being formed at its 60 ends with means for engagement with abutting rails and with the apertures of the first named transversely extending portion.

3. A metallic tie of the character described having spaced from one end a transversely 65 extending depressed portion and having struck up from the tie an upwardly extending eye intersecting said depressed portion, a rail clamping member attached to one end of the tie and having a vertical flange extending transversely of the tie, the ends of the flange being perforated, a second clamping member having a base and an upwardly 70 extending flange, the base being formed with a transversely extending depressed portion 75 adapted to fit in the depressed portion of the tie and with a longitudinally extending slot adapted to receive said eye, the transversely extending flange of the last named clamp being formed with longitudinally extending 80 studs adapted to pass through apertures in abutting rails and through the apertures in the first named transversely extending flange.

4. A rail tie of the character described 85 comprising a sheet metal body having laterally depending flanges, rail clamps at the ends of the tie, each clamp comprising a plate riveted to the tie, the end of the plate being upwardly bent to form a transversely 90 extending flange and the sides of the plate being upwardly bent to form abutting flanges, the face of the tie inward of said rail clamps being formed with transversely 95 extending depressed portions and with longitudinal slots crossing said depressed portions, the material of said slots being bent upward to form eyes, and rail clamps opposed to the first named clamps, each consisting of a plate of sheet metal, the end of 100 the plate being upwardly bent to form a transverse flange adapted to confront the first named transverse flange, the end of the plate remote from said flange being transversely depressed and longitudinally slotted, 105 the slot being large enough to receive said eye, and a transverse pin adapted to be inserted through said eye and to rest in the depressed portion of the plate and hold the plate in place.

In testimony whereof I hereunto affix my signature.

EDWARD A. BOOHER.
